UNITED STATES PATENT OFFICE.

FLOYD J. METZGER, OF NEW YORK, N. Y., ASSIGNOR TO AIR REDUCTION COMPANY, INC., A CORPORATION OF NEW YORK.

ELECTRODE.

Application filed July 29, 1920. Serial No. 399,882.

To all whom it may concern:

Be it known that I, FLOYD J. METZGER, a citizen of the United States, residing at New York city, in the county of New York, State 5 of New York, have invented certain new and useful Improvements in Electrodes; and I do hereby declare the following to be a full, clear, and exact description of the invention, such as will enable others skilled in the art 10 to which it appertains to make and use the same.

This invention relates to electrodes employed as terminals between which electrical discharges are caused to pass through a 15 gaseous medium or a substantial vacuum and has particular application to the production of luminescent discharges through tubes or lamps which are thereby made to glow. It is to be understood that 20 tubes or lamps are known in which discharges are passed between electrodes through an atmosphere containing gases under various pressures both above and below atmospheric pressure and through a substantial 25 vacuum produced by exhausting the tube or lamp.

In such tubes or lamps, which may be of any desired shape and which may have the electrodes at opposite ends or in more closely 30 spaced relation, the electrodes have been constructed heretofore of metal, or other conducting material such as copper or carbon for example. These electrodes are connected to lead-in wires which are sealed through 35 the glass of the tube or lamp. If unsupported, the electrodes vibrate more or less, owing to shocks, and are separated from the lead-in wire. It has been suggested to support the electrodes in various ways as by a 40 ring of glass beads disposed between the electrodes and the wall of the tube or lamp, but this introduces additional constructional difficulties, and the arrangement is not wholly satisfactory.

45 These and other considerations have directed a search for a more satisfactory electrode which may be rigidly supported in the tube or lamp and which will not therefore vibrate and become separated from the lead- 50 in wire under repeated shocks. It has been discovered as a result of investigations that a very satisfactory electrode may be inexpensively constructed of glass which may be sealed into the glass of the tube or lamp to

form an integral part thereof. To complete 55 the electrode a sheath of a conducting metal, preferably copper, may be mounted on the glass support which projects into the tube or lamp, the sheath being connected to a lead-in wire which is sealed through the glass 60 support. In this manner one or more electrode surfaces may be formed on the glass support for the purposes hereinafter indicated. The copper or other conducting metal is preferably deposited electrolytically on 65 the glass but other methods of applying the metal may be employed. The sheath may be separately formed and spun, or otherwise fastened on the glass support, or the metal may be sprayed onto the glass by means well 70 known to the art.

In depositing the conducting metal according to the preferred method, the glass support is provided with a conductor sealed therethrough and projecting slightly at 75 the surface to be treated. The glass support is roughened or etched by subjecting it to the action of hydrofluoric acid or of a fluoride mixture capable of etching glass in accordance with well understood principles. 80 The etched glass is then dipped in an alcoholic solution of silver nitrate after which the film of silver nitrate adhering to the surface is subjected to the action of hydrogen sulphide to produce a conductive coating of 85 silver sulphide. Of course, other means of providing a conductive coating on the glass may be employed. The glass with its conductive coating is arranged as the cathode in an electrolytic bath consisting for example of a copper sulphate solution acidified with nitric acid and a current is passed 90 through the electrolyte to deposit copper on the glass. A closely adherent coating of copper is thus obtained which forms the 95 permanent conducting surface of the electrode. If metallic coatings other than copper are desired, the electrolyte is correspondingly modified in accordance with the well known practice of electrolytic deposition of metals. If two or more conducting surfaces are desired on the glass support, the surface which it is not desired to plate may be covered, as by a rubber band, or by otherwise insulating a portion of the surface during electrolysis; or the desired portion of the coating may be removed after deposition 100 of the metal. The projecting conductor 105

sealed through the glass will be in contact with the conductive coating on the surface of the glass.

An electrode produced in the manner described is ideal for the purposes in view. It is comparatively light in weight; it may be sealed into the glass of the tube or lamp and will not separate therefrom under shocks; the coating may be comparatively thin and will not carry quantities of occluded gases which are detrimental to the objects to be attained and difficultly removable. The invention facilitates fabrication of the tube or lamp in an inexpensive manner. Electrodes made in accordance with the invention have been employed, particularly in tubes or lamps containing neon, and have proved to be highly satisfactory. The invention, is not however, limited to such use, since it obviously has a broader application.

It is the object therefore of the invention to provide a novel, inexpensive and satisfactory electrode adapted for use in tubes and lamps which are illuminated by electrical discharges and for other analogous purposes. Certain applications of the invention are illustrated, by way of example, in the accompanying drawing, in which,

Figure 1 is a view in elevation of a luminescent tube with the improved electrodes embodied therein;

Figure 2 is a view in elevation of an electrode;

Figure 3 is a section through an electrode; Figure 4 is an elevation of a glow lamp embodying the invention and

Figure 5 is a view in elevation of another form of electrode.

Referring to the drawing 5 indicates a tube which may be under vacuum or filled with a gas at any desired pressure, neon for example. The tube 5 is preferably provided with enlarged ends 6 to receive the electrodes 7 which are made of glass and are sealed into the ends 6 as indicated at 8. The electrodes 7 are provided as hereinbefore described with coatings 9 of conductive metal deposited or otherwise applied to the electrodes, and with conductors 10 sealed through the wall of the electrode to make contact with the coating 9. When the two electrodes 9 are connected to a source of current at suitable voltage the tube is caused to glow. As will be readily understood the electrodes form an integral part of the tube and are rigid and not subject therefore to vibration such as ultimately causes breakage of the conductor in tubes provided with the usual metal electrodes.

Occluded gases may be readily driven from the relatively thin coating of conductive metal on the electrode and the preparation of the tube is thus facilitated.

In Fig. 4 of the drawing a glow lamp is illustrated and consists of a bulb 11 in

which an electrode 12 is supported. The electrode 12 is made of glass and is sealed into the bulb 11 at 13. A shell or coating 14 of conductive metal is provided on the glass electrode 12 and is electrically connected to a conductor 15 which is sealed through the electrode. A band 16 of conductive metal surrounds the electrode 12 below the coating 14 and is electrically connected to a conductor 17 which is sealed through the electrode. The band 16 is spaced from the coating 14 a distance less than the minimum spark gap for the gas in the bulb at the pressure employed and consequently when the conductors are connected to a source of current at suitable voltage, a glow is set up within the bulb. The advantages of the glass electrode as hereinbefore described are equally apparent in this form of the invention.

In Fig. 5 another form of electrode is illustrated which may replace the electrode in Fig. 4. A spherical or similarly shaped surface 18 of a glass support is divided into two parts and is provided with separate shells or coatings 19 of conductive metal. An extension 20 on one side permits sealing of the electrode in a bulb and provides a conduit for the conductors 21 and 22 which are sealed through the glass and are electrically connected to the respective shells or coatings. The space between the shells or coatings 19 is less than the minimum spark gap for the gas at the pressure used and consequently when the conductors 21 and 22 are connected to a source of current at suitable voltage the discharge between the electrodes will produce the desired lighting effect.

The term "tube" as used in the claims here-with is intended to include tubes, bulbs and receptacles of various shapes in which the electrodes may be supported.

Various changes may be made in the form, arrangement and materials employed without departing from the invention which comprehends a support having a conductive surface and adapted to be sealed by fusion into a surrounding glass wall to produce a gas tight joint.

I claim:

1. An improvement in electrodes employed in effecting electrical discharges, which comprises a tube, a support within the tube, a sheath of conducting metal on the support, said sheath being relatively thin and therefore comparatively free from occluded gases and a conductor connected to the sheath.

2. An improvement in electrodes employed in effecting electrical discharges, which comprises a tube, a support within the tube, a coating of conducting metal electrolytically deposited on the support, said coating being relatively thin and there-

fore comparatively free from occluded gases and a conductor connected to the coating.

3. An improvement in electrodes employed in effecting electrical discharges, 5 which comprises a support, conducting coatings of metal on the surface of the support, the space between said coatings being less than the minimum spark gap for the gas within the tube at the pressure used and conductors connected to the coatings.

4. An improvement in electrodes employed in effecting electrical discharges, which comprises a glass support, thin coatings of conducting metal on the surface of 15 the support, the space between said coatings being less than the minimum spark gap for the gas within the tube at the pressure used and conductors sealed through the wall of the support and connected to the coatings.

20 5. An improvement in illuminating devices and the like, depending upon electrical discharges, which comprises a chamber, a non-metallic support fused into the wall of said chamber, a coating of conducting

metal on the support, said coating being 25 divided to provide two conducting surfaces, the space between said surfaces being less than the minimum spark gap for the gas within the tube at the pressure used and conductors connected to the respective con- 30 ducting surfaces.

6. An improvement in illuminating devices and the like, depending upon electrical discharges, which comprises a chamber, a non-metallic support fused into the wall of 35 said chamber, a coating of conducting metal on the support, said coating being divided to provide two conducting surfaces, the space between said surfaces being less than the minimum spark gap for the gas within 40 the tube at the pressure used and conductors connected to the respective conducting surfaces, said conductors being sealed through the wall of the support.

In testimony whereof I affix my signature. 45

FLOYD J. METZGER.
